CLAMP FOR AN OPERATING TABLE SIDE RAIL AND THE LIKE

Fred K. Storm, Allen St., Glendale, Calif., and Eldridge
H. Smiley, 9529 Marshall St., Rosemead, Calif.

Filed May 24, 1962, Ser. No. 70,272

Term of patent 14 years

(Cl. D54—13)

FIG. 3

FIG. 4

FIG. 1

FIG. 2

FIG. 1 is a perspective view taken from the front and right side of a clamp for an operating table side rail and the like embodying our new design;

FIG. 2 is a perspective view taken from the rear thereof; FIG. 3 is a right side elevational view thereof; and FIG. 4 is a top plan view thereof.

The fragmentary showing of a side rail and vertical post in FIGS. 1 and 2 is for illustrative purposes only.

We claim:

The ornamental design for a clamp for an operating table side rail and the like, as shown and described.
